[57] CLAIM

The ornamental design for a hand scraper, substantially as shown and described.

DESCRIPTION

FIG. 1 is a perspective view of a hand scraper, showing my new design;

FIG. 2 is a left side elevational view, the right side being identical thereto;

FIG. 3 is a top plan view thereof;

FIG. 4 is a bottom plan view thereof;

FIG. 5 is a front elevational view; and

FIG. 6 is a rear elevational view thereof.

In FIG. 4, the pattern of teeth is understood to repeat uniformly and continuously across the entire indicated area.

FIG. 1

FIG. 3

FIG. 5

FIG. 2

FIG. 6

FIG. 4
